UNITED STATES PATENT OFFICE.

FRANK P. ROESCH, OF CHICAGO, ILLINOIS, ASSIGNOR TO STANDARD STOKER COMPANY, INCORPORATED, A CORPORATION OF DELAWARE.

STOKER.

Application filed August 5, 1924. Serial No. 730,170.

This invention relates to locomotive stokers and particularly to that type of stoker wherein coal is conveyed from the tender to the locomotive fire box through a tube or conduit, there being suitable mechanism in the tube, such as a screw, for moving the coal therethrough.

The numerous objects and advantages of my invention will appear in the following description taken in connection with the accompanying drawing wherein,

Fig. 1 is a diagrammatic view, partly in section and partly broken away, of a locomotive having embodied therein, one form 15 of my invention.

Fig. 2 is an enlarged sectional view of the locomotive fire box taken on line 2—2 of Fig. 1 and looking downwardly at the main grate and the delivery end of the coal conveying conduit; the protecting grate which surrounds the delivery end of the conduit being removed.

Fig. 3 is a sectional view taken on the line 3—3 of Fig. 2 showing in elevation the central, grate supporting, bar.

Fig. 4 is an enlarged detailed view of the delivery end of the coal conveying conduit and showing the protecting grate surrounding the conduit.

Fig. 5 is a section on the line 5—5 of Fig. 4, certain of the parts being shown in elevation.

The type of stoker disclosed in the drawings is one in which the fuel is delivered to the fire through a tube or conduit which enters the fire box beneath the grate and thence passes upward through the grate and terminates in a delivery opening above the fire, there being suitable means, such as

steam jets, for spreading the fuel over the fire as it passes out of the delivery opening. In this type of stoker it is customary to provide an auxiliary or protecting grate around the upper end of the delivery conduit. This

auxiliary grate is usually similar to a skirt in form. It fits around the upper end of the conduit and extends outwardly and downwardly to the main grate and forms a space between the auxiliary grate and conduit,

which space is covered at its top and usually opens downwardly to the ash pit. This space is normally supplied with air which passes into the combustion chamber through openings in the auxiliary grate, thus assisting in the complete combustion of the

fuel. The auxiliary grate keeps the fire away from the delivery conduit and the current of air flowing through the space between the conduit and the auxiliary grate prevents the conduit, as well as the auxiliary 60 grate, from becoming overheated. Inasmuch as this space is covered at the top, coal which passes out of the delivery opening cannot fall into this space, but instead is forced by the steam jets over the auxiliary 65 grate onto the fire.

The present invention seeks to overcome certain objectionable features present in prior locomotive stoker constructions of the character above described.

A steam locomotive comprises a longitudinal frame which serves as a support for the boiler and fire box construction. The boiler is rigidly secured to its frame at its forward end and is permitted at its rear end 70 to move on the frame so as to take care of expansion and contraction of the boiler. When a stoker construction as above described is applied to a steam locomotive, it has in the past been customary to secure the 75 upwardly extending portion of the fuel delivery conduit, at its lower end, to the locomotive frame and to support the auxiliary grate on the fire box construction. Inasmuch as there is considerable movement of the fire box on the frame, the auxiliary grate which tends to move with the fire box will be pushed against the upper end of the conduit, thus bending or displacing the conduit. In the embodiment of the invention herein 80 disclosed, I prevent this tendency to bend or displace the conduit by providing a construction which will permit a considerable movement of the auxiliary grate and which at the same time will maintain the space between the auxiliary grate and conduit closed 85 so as to prevent coal from falling into this space.

Referring now in detail to the drawings, Fig. 1 represents a locomotive comprising 100 a boiler 10 having a fire box 11 and 12 represents a main supporting frame of the locomotive. The cylinders 14 are formed rigid with the frame 12 at its forward end and these cylinders are rigidly secured at 105 16 to the forward end of the boiler. Various means may be provided for supporting the boiler rear of its forward end on the frame 12 so as to permit longitudinal movement 110 between the two. In the construction 110

shown, such means comprises plates 17 which may bend longitudinally of the boiler, and at the same time, be sufficiently strong in a vertical direction to support the weight of the boiler.

In the fire box 11 is located the main grate 20 which comprises rocking bars or members 21 and 22 adapted to be actuated by suitable means not shown. The rocking members are journaled at their inner ends in centrally located supporting bars 24 and 25 and at their outer ends in bars 27, which are secured to the sides of the fire box. The central bar 25 is forked at its rear end as shown at Fig. 2, and the rear grate bars 22, which are journaled in the forked portion of the bar 25, are somewhat shorter than the remaining bars 21, thus leaving an opening 28 in the main grate. Bars 24 and 25 are supported at their outer ends by lugs 29 secured to the fire box walls and at their inner ends by a transverse bar 32 secured at its ends to the side walls of the fire box.

35 represents a conveyor tube or conduit which extends forwardly from the tender under the deck 36 of the locomotive and under the mud ring 37 of the boiler into the ash pit 38. From this point it is formed with an upwardly extending portion 39 which terminates in the delivery opening 40 above the normal level of the fire. The conduit 35 is provided with suitable means not shown for forcing the coal therethrough and delivering the same through the opening 40. As the coal passes from the opening 40, it is caught by steam jets which issue through openings 45, formed in a casting 46 located above the opening 40 and is carried by these jets laterally over the fire.

40 Partially surrounding the upper end of the portion 39 of the conduit is an auxiliary or protecting grate 47, which comprises cast metal sections 48 and 49, both of which are spaced from the conduit 35 and form a chamber 50 which opens downwardly into the ash pit 38. Section 49 of the protecting grate is supported on the forked portion of the bar 25, this section being provided with lugs 51 at its lower edge to maintain the section in position on the bar 25. The section 48 rests on the top of section 49 and is formed with lugs similar to lugs 51 for the purpose of preventing lateral movement of the section 48 on section 49. Lightly fitting the top of the portion 39 of the conduit and resting at its inner edge on lugs 60 projecting from the outer face of the conduit 37 is a metal plate 53. The top of the plate is smooth and in the form illustrated, is flat. The plate 53 is preferably thickened somewhat around its central opening and ribs 54 extend from the thickened portion outwardly to the outer edge of the plate. As shown in Fig. 5, the plate 53 is supported some distance above the top of the grate

section 48. The grate sections 48 and 49 are formed with openings 56 and these openings, together with the opening between the top of the grate section 48 and the plate 53, serve to permit air which enters the chamber 50 from the ash pit to flow outwardly into the combustion chamber, thus assisting in the complete combustion of the fuel. Furthermore, this air in passing through the chamber 50 into the combustion chamber, serves to maintain the conduit 39, plate 53, and grate 47 cool.

From the above construction, it will be seen that in case the grate 47 moves relatively to the conduit 53, under the influence of the expansion and contraction of the boiler 10, that the grate 47 will merely move under the plate 53 and will not move the plate nor the upper end of the conduit 39.

While I have shown the portion 39 of the conduit 35 as vertical, it will be understood that in certain constructions the portion 39 may be inclined to the vertical.

I claim:

1. In a locomotive, a main supporting frame, a boiler and fire box construction mounted thereon, a conduit for delivering fuel to said fire box, comprising an upwardly extending portion rigidly secured to said frame and terminating in a fuel delivery opening in the combustion chamber, a protecting grate mounted on said boiler and fire box construction and forming with said conduit a downwardly open space about said conduit, and means covering the space between said grate and conduit at the delivery opening, the parts being so arranged that relative movement between said grate and conduit due to the expansion of said boiler and fire box construction is permitted.

2. In a locomotive, a main supporting frame, a boiler and fire box construction mounted thereon, a conduit for delivering fuel to said fire box, comprising an upwardly extending portion rigidly secured to said frame and terminating in a fuel delivery opening in the combustion chamber, a protecting grate mounted on said boiler and fire box construction and forming with said conduit a downwardly open space about said conduit, and a plate surrounding and fitting the delivery end of said conduit and extending over the top of said grate, said parts being so spaced and arranged that relative movement between said grate and conduit due to the expansion of said boiler and fire box construction is permitted.

3. In a locomotive, a main supporting frame, a boiler and fire box construction mounted thereon, a conduit for delivering fuel to said fire box, comprising an upwardly extending portion rigidly secured to said frame and terminating in a fuel delivery opening in the combustion chamber, a protecting grate mounted on said boiler and

- fire box construction and forming with said conduit a downwardly open space about said conduit, and a plate carried by and surrounding the delivery end of said conduit, said plate extending over the top of said grate and spaced therefrom so as to permit relative movement between said grate and conduit due to the expansion of said boiler and fire box construction.
5. In combination with a fire box, an upwardly extending conduit adapted to deliver coal thereto, a protecting grate surrounding and spaced from said conduit, and a plate covering the space between the grate and conduit, the parts being formed to permit the passage of air between said plate and the upper edge of said grate, and the grate and conduit parts being spaced and arranged to permit relative movement between them due to expansion and contraction of the supporting constructions for said parts. 30
10. 4. In a locomotive, a main supporting frame, a boiler and fire box construction mounted thereon, a conduit for delivering fuel to said fire box, comprising an upwardly extending portion rigidly secured to said frame and terminating in a fuel delivery opening in the combustion chamber, a protecting grate mounted on said boiler and fire box construction, and a plate surrounding and fitting the delivery end of said conduit and forming with said conduit a downwardly open space about said conduit, said plate extending over the upper portion of said grate and being formed with ribs on its under surface whereby an air passage is provided between the grate and plate, and all of said parts being so arranged as to permit relative movement between said grate and conduit as the boiler and fire box construction expands and contracts. 35
15. 5. In a locomotive, a main supporting frame, a boiler and fire box construction mounted thereon, a conduit for delivering fuel to said fire box, comprising an upwardly extending portion secured to said frame and terminating in a fuel delivery opening in the combustion chamber, a protecting grate construction mounted upon said boiler and fire box construction and surrounding and spaced from said conduit, and means covering the space between said grate construction and conduit in such a manner as will permit a relative movement between 40 said conduit and grate construction. 45
20. 6. In a locomotive, a main supporting frame, a boiler and fire box construction mounted thereon, a conduit for delivering fuel to said fire box, comprising an upwardly extending portion secured to said frame and terminating in a fuel delivery opening in the combustion chamber, a protecting grate construction mounted upon said boiler and fire box construction and surrounding and spaced from said conduit, and means covering the space between said grate construction and conduit in such a manner as will permit a relative movement between 50 said conduit and grate construction. 55

FRANK P. ROESCH.
